(57) CLAIM

The ornamental design for a stage light, as shown and described.

DESCRIPTION

FIG. 1 is a front, right and top perspective view of a stage light, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 2 thereof; and,

FIG. 10 is an enlarged view of portion 10 of FIG. 2 thereof. The broken lines shown in the drawings illustrate portions of the stage light that form no part of the claimed design.

The dot-dash broken lines in FIGS. 2, 9 and 10 are for annotating the enlargements only and form no part of the claimed design.
